(57) **CLAIM**

The ornamental design for a steering pad for an automobile, as shown and described herein.

DESCRIPTION

FIG. 1 is a left side perspective view of a steering pad for an automobile.

FIG. 2 is a right side perspective view of a steering pad for an automobile.

FIG. 3 is a front view of a steering pad for an automobile. FIG. 4 is a top plan view of a steering pad for an automobile. FIG. 5 is a left side perspective view of a steering pad for an automobile.

FIG. 6 is a right side view of a steering pad for an automobile; and,

FIG. 7 is a bottom view of a steering pad for an automobile. The broken lines in the drawings illustrate portions of the steering pad for an automobile that form no part of the claimed design.
